CLAIM

The ornamental design for a multi-function inkjet printer, substantially as shown and described.

DESCRIPTION

FIG. 1 is a perspective view of a multi-function inkjet printer, in accordance with the present invention;

FIG. 2 is a front view thereof;

FIG. 3 is a top plan view thereof;

FIG. 4 is a left side elevational view thereof;

FIG. 5 is a right side elevational view thereof; and,

FIG. 6 is a rear elevational view thereof.

The bottom view has been omitted because it forms no part of the claimed design.

The broken lines are for purposes of illustration only and form no part of the claimed design.
